FASTENING TAB FOR A SCREEN DOOR GRILLE OR THE LIKE

Walter A. Curtze, Erie, Pa.

Application December 28, 1956, Serial No. 44,353

Term of patent 14 years

(Cl. D54—2)

Fig. 1 is an elevation of a fastening tab for a screen door grille or the like. The other side of the tab is plain.

Fig. 2 is an edge view of the grille.

The essential features of my design reside in the portions shown in full lines.

I claim:

The ornamental design for a fastening tab for a screen door grille or the like, substantially as shown and described.
